UNITED STATES PATENT OFFICE

2,169,752

FURNITURE

Andrew S. Wright, Springfield, Mass.

Application December 10, 1937, Serial No. 179,128

1 Claim. (Cl. 211—149)

This invention relates to improvements in furniture and is directed more particularly to an improved table-like device which has parts adapted to move into and out of supporting position.

5 One of the principal objects of the invention is the provision of a piece of furniture which includes one or more pivoted supporting members adapted to move between a horizontal position and a relatively vertical position. Thus, when 10 the member is in its horizontal position, the device is adapted to function in the same manner as a table or tray-stand while when the supporting member is in its other position, the device may be used for various other purposes, such as 15 a fire-screen or the like.

Still another object of the invention is the provision of a piece of furniture which is decorative so as to be an asset to the appearance of a room and which, at the same time, is simple 20 in form so as to be economical to manufacture.

It is still another object of the invention to provide a device of the class about to be described wherein there is a supporting member which is arranged to be normally in a vertical 25 position but which is pivoted in such a way as to be capable of being moved to a horizontal supporting position, only to automatically assume its vertical position when released in a manner which will appear.

30 Various other objects and advantages of the invention will become more apparent after a reading of the following description and reference will be had to the accompanying drawing, wherein—

35 Fig. 1 is a front elevational view of the device of the invention with supporting members in vertical position;

Fig. 2 is a similar view showing the supporting members in horizontal position;

40 Fig. 3 is an end elevational view showing the supporting members in horizontal position; and

Fig. 4 is a sectional view on a large scale to explain certain features of construction.

45 Referring now to the drawing more in detail, the invention will be fully described.

A frame member is provided and while it may vary in form it preferably includes a pair of spaced uprights 2 extending upwardly from a base and having a spacer bar 4 connecting them 50 adjacent their upper ends. The material of which these parts are made may vary but wood has been found to be preferable as it is not objectionably costly, is light in weight yet suitably rigid, and is readily decorated, as may be desirable.

The base may be formed in several ways but, in the form shown, it consists of a pair of elongated parts 6 spaced apart and having connectors such as 8 and 10 extending between their opposite ends. The uprights 2 then extend upwardly from the central portions of parts 6 and while they are preferably secured thereto, they may be removable for knock-down purposes as by having their lower ends fit into sockets provided in the parts 6.

One or more panels or supporting members 12 10 are pivoted between the uprights 2 as by dowels or pins 14. It will be noted that the pivots 14 are not in the exact center of the ends of the panels.

That is to say, the distance between the pins 15 and the lower side of each panel is greater than the distance between the pins and the upper side of the panel. Thus, as will be obvious, one side 20 of each panel (the lower side with reference to Fig. 1 and the right-hand side with reference to Fig. 3) will be more or less heavier than its opposite side and the reason for this will now be described.

What I call a connector member 16 is hinged, as at 15, to the panels 12. Where there are two panels, as shown, the upper end of the member 16 is hinged at 15 to the marginal edge portion 25 of the lighter side of the upper panel and an intermediate portion thereof is hinged to the marginal edge portion of the lighter side of the 30 lower panel.

It will be apparent that the panels 2 being, as stated, heavier on one side than on the other, will naturally, if unrestrained, swing on their pivots to the vertical position shown in Fig. 1. 35 In this vertical position, as I have suggested above, the device may be conveniently used as a fire screen or the like, the panels 2 presenting a relatively unbroken vertical surface. For this reason, I find it suitable to ornament the upper surfaces 40 of panels 2 as Fig. 1 indicates.

However, as also suggested above, the panels 2 are adapted to be swung to and maintained in the horizontal supporting position shown in Figs. 2 and 3. While in the position, the device may 45 be readily moved from place to place and used as a table-like device from which to serve such things as tea, cookies, etc.

For this reason, it is, of course, necessary to provide some means for preventing the off-centered panels from collapsing to their normal vertical position. Accordingly, I provide a releasable connection between the panels and the frame member which is adapted to maintain the panels 2 horizontal when desired.

Accordingly, I provide means whereby the connector 16 above described may releasably engage the frame. Such means may likewise vary in form but preferably includes a projection or outwardly-extending pin 18 on the rod 8 and a suitable aperture 20 in the lower end portion of member 16 for receiving the pin 18.

The panels 2 are so spaced, the connector 16 of such length, and the releasable-engaging means so located that by merely pressing on the heavier side (the right-hand side in Fig. 3) of the panel 2 the same is swung on its pivots 14 to a horizontal position and the connector 16 is carried outwardly thereby so as to gravitate to a position at right angles to the panel. In this position the pin 18 automatically receives the hole 20 as the connector, being made of relatively thin material, has a somewhat yieldable and free lower end portion, as shown in Fig. 3, and as the said pin 18 and hole 20 are so spaced and located relative to one another that they automatically engage each other when the parts are in the position shown in Fig. 3.

Thus the connector 16 is held in the position shown in Figs. 3 and 4 so that the panels 2 are releasably maintained in supporting position.

On the other hand, the arrangement is such that when it is desired to have the panels assume their normal or vertical position, one may, by merely urging the member 16 outwardly, as with a foot, hand or the like. It will be obvious that the weighted panels then swing to a vertical position with the connector following them to lie adjacent the bottom of the panels.

It will be seen that the arrangement is such that when the panels are in vertical position, the decorated sides of the panels are outermost and the hinged connector is more or less hidden from view. This makes for an attractive fire

screen or the like, while, at the same time, the device may be readily set up in, or knocked down from a supporting position.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

A fireplace screen comprising in combination, a vertical frame member having a substantially horizontal base, a pair of leaf members within said frame member, pivotal connections between said frame member and opposite ends of said leaf members whereby said leaf members are swingable between a vertical position and a horizontal position, a vertically-disposed connecting member of a certain length having its upper end portion hinged to the upper one of said leaf members adjacent a side edge thereof and its intermediate portion hinged to the lower one of said leaf members adjacent a side edge thereof and its lower end portion extending freely downwardly therefrom, said connecting member being movable with said leaf members between a position substantially in parallelism with and closely adjacent the under surfaces of said leaf members when the same are in vertical position and a position substantially at right angles to said leaf members when the same are in horizontal position, the lower end portion of said connecting member being relatively yieldable and said base and the lower end portion being provided with engageable parts which are adapted to be urged into releasable engagement when said leaf members are swung to horizontal position.

ANDREW S. WRIGHT.
